United States Patent Office.

HENRY SPLITDORF, OF NEW YORK, N. Y.

Letters Patent No. 96,992, dated November 16, 1869.

IMPROVEMENT IN TELEGRAPH-SOUNDERS.

The Schedule referred to in these Letters Patent and making part of the same.

To all whom it may concern:

Be it known that I, HENRY SPLITDORF, of the city, county, and State of New York, have invented a new and useful Improvement in Telegraphic Sounders; and I do hereby declare the following to be a full, clear, and exact description thereof, which will enable those skilled in the art to make and use the same, reference being had to the accompanying drawing, forming part of this specification, in which drawing—

Figure 1 represents a plan or top view of this invention.

Figure 2 is a longitudinal vertical section of the same.

Similar letters indicate corresponding parts.

This invention consists in supporting the sounding-box of a telegraphic sounder at an elevation above the base of the instrument, on one or more detached supports, in such a manner that the effect of said sounding-box is materially improved, and that a telegraphic sounder is obtained, which gives a clear and distinct sound, enabling the operator to understand the message received without difficulty.

In the drawing—

The letter A designates the base, on which are supported the electro-magnets B, their armature C, the sounding-box D, and the tension-regulator E of the armature-spring, the whole composing the various parts of a telegraphic sounder.

In telegraphic sounders, as heretofore made, the sounding-box is fastened down directly upon the base A, and its effect in increasing the volume of the sound

is partially lost, since the bottom of the box, being firmly connected to the base A, is unable to partake of the vibrations due to the sound.

This defect I have overcome by placing the sounding-box D, in my sounder, at an elevation above the base A, said sounding-box being either supported on one or more columns F, or suspended from arms which might be substituted for the columns.

By these means the bottom of the sounding-box, as well as its top and sides, is free to vibrate, and if the armature-lever C is brought down upon the anvil G, a clear and distinct sound is produced, whereby the operator is enabled to understand the message received, without the liability of an error.

It is obvious that my improvement is applicable to telegraphic sounders of every description, but it is particularly intended for main-line sounders.

I do not claim, as my invention, the arrangement of a sounding-box, in combination with the armature-lever of a telegraphic instrument; but

What I claim as new, and desire to secure by Letters Patent, is—

The sounding-box D, elevated on posts F, and having the anvil G secured directly on its top, and openings in its sides, to increase the sound and allow the passage of the tightening-spring, substantially as and for the purpose described.

HENRY SPLITDORF.
